Patented Aug. 31, 1920.

FIG. 1.

FIG. 3.

UNITED STATES PATENT OFFICE.

FRANK LEMING, OF HINGHAM, MASSACHUSETTS.

MACHINE FOR RE-FORMING AMMUNITION-SHELL CASINGS.

1,351,389.

Specification of Letters Patent. Patented Aug. 31, 1920.

Application filed July 24, 1919. Serial No. 312,966.

To all whom it may concern:

Be it known that I, FRANK LEMING, a citizen of the United States, residing at Hingham, county of Plymouth, State of Massachusetts, have invented a certain new and useful Improvement in Machines for Re-Forming Ammunition-Shell Casings, of which the following is a specification, reference being had therein to the accompanying drawings.

When a shell has been exploded, the metallic casing is more or less mutilated or bent, so that it has to be trued up before it is fit to be refilled for use again, because it is necessary that it should have on its exterior surface a smooth fit for the bore of the gun. So far as known to me this has heretofore been done by hand or by hand machines and not automatically, and the process has therefore been very slow.

The object of my invention is to provide an automatic mechanism into which the empty casing need only to be fed and the machine will automatically reform the casing and eject it. The invention consists substantially in providing a rotary drum with a plurality of dies arranged in a series in a circle which is concentric with the drum, and into which the casings may be successively fed, presser mechanism which automatically presses the casing into the die, and an ejector mechanism which at a certain point in the rotation of the drum ejects the reformed casing from the die, leaving the die empty for the reception at the proper feeding place of another casing to be reformed.

The invention will be fully understood from the following description when taken in connection with the accompanying drawings and the novel features thereof will be pointed out and clearly defined in the claims at the close of this specification.

In the drawings, Figure 1 is a vertical section of a machine embodying my invention.

Fig. 2 is a sectional view on line 2—2 of Fig. 1.

Fig. 3 is a detailed view of a portion of the drum showing one of the presser devices and the actuating cam therefor.

Referring now to the drawings, 1 is the

rotary drum rotatably mounted on a shaft 2, said shaft being mounted in bearings 3, 4 within the case 5. Ball bearings 6 are preferably provided between the end of the drum and the end of the case 5. The drum is provided with an annular gear 7 which engages with a worm 8 mounted on a driving shaft 9 by means of which the drum is constantly rotated. Preferably the drum is mounted horizontally on the shaft 2. The case 5 for the drum is mounted on any suitable support, as for instance the legs 10.

The drum is provided with a plurality of dies 11 set into one end of the drum and arranged in the head of the drum in a concentric series around the shaft 2. Inasmuch as the drum itself may be made of comparatively soft, inexpensive metal, the dies 11 are preferably made separate from the drum, of hard steel set into sockets in the head of the drum, making them separate from the drum. Not only is it unnecessary for the drum itself to be made of as expensive or hard material as the dies, but also the dies may be renewed from time to time without discarding the drum. These dies should be firmly secured within the sockets in the drum by some suitable means. In order to avoid driving them in so tight that they cannot be removed when desired, I prefer to employ some holding or clamping mechanism so that although the dies are fitted sufficiently tight so that there will be no play, yet they need not be so tight but that they may be removed if at any time it is desired to take them out and substitute other dies for them. The clamping means which I employ consists of a member 12 which fits into a grooved recess in the drum at the side of the socket which receives the die 11, said clamp having a semicircular inner portion which engages the periphery of the die 11 and having at its outer end a semi-annular flange 13 which engages over the outer end of the die. Said clamp is secured to the drum by screws 14 which pass through lugs 15 extending from the sides of the clamp and are screwed into the drum.

The inner periphery of each die is circular in cross-section and perfectly smooth and of a diameter equal to the exterior di-

ameter of the main body of the casing 16 of the shell which is to be reformed.

The drum is provided with a plurality of cylindrical holes or recesses 17, one adjacent 5 to each one of the dies and parallel therewith into which loosely fits one leg 18 of a sort of siphon shaped plunger press, the short arm 19 of the siphon shaped member constituting the presser which is adapted to 10 be brought into alinement with the entrance end of the die 11 or with the shell casing when inserted into the die. Preferably the presser arm 19 has a presser head 37 separable from the arm 19, so that varying sizes 15 may be employed with the same arm. The arm 18 of the presser member is seated upon a spring 20 which normally holds or tends to hold the presser end of the short arm 19 some distance away from the end of the 20 drum. Said arm 18 is not only slidable longitudinally in the socket in which it is set, but it is also rotatable therein.

Journalled in the arched end 21 of said presser member is a roller 22, which at certain stages in the rotation of the drum is 25 adapted to be engaged by a cam 23 which so long as the said roller engages with the high part of the cam holds the presser member in its most pressed in position, as 30 shown in Fig. 3, but when the roller rides off of the high part of the cam, the spring 20 will thrust the presser member outward.

Each presser member carries on one side thereof at a point outside of the end of the 35 drum, a projection 24. A cam 25 is mounted on the frame in a certain position to be engaged by the projection 24 on each presser member. At a certain point in the rotation of the drum the said projection 24 rides up 40 on the surface of the cam 25 which will cause the said presser member to swivel on its axis far enough to turn the short presser arm 19 out of alinement with the mouth of the die.

An ejector stem 26 passes loosely through 45 a hole 27 in the base 28 of the die and at its inner end is connected with a foot 29 which is slidable in guideways in the drum and is bifurcated at its end. Within the forked end of the foot 29 there is journaled a roller 30 on the shaft 31, said roller riding on a cam 32 which is so shaped that at the proper time the ejector member will be forced to the right, as shown in Fig. 1. The presser foot 29 is formed with a key 55 34 which moves in a key-way 35 in the drum 1, in order to keep the rollers 30 in proper alinement with the cam track 32. Said ejector stem 26 is provided with a head 33 which is adapted to engage the inner face of 60 the head of the shell casing 16. The cam 32 is so formed that when in rotation of the drum the shell casing has come around to the proper position after having been forced into the die to reform the shell casing, said 65 ejector will be forced outward thereby pro-

jecting the shell casing outward from the die. This ejection takes place sometime shortly after the presser member has been turned out of alinement with the end of the shell casing, that is after it has passed the 70 cam 25, as shown in Fig. 2. After the shell casing has been pushed outward by the ejector it may be easily removed by hand or by any suitable mechanism. If desired the movement of the ejector 26 may be sufficient in extent to completely eject the shell casing.

After the shell casing has been ejected, the presser arm 19 being still out of alinement with the die, another shell casing which is 80 to be reformed may be introduced into the mouth of the die, either by hand or by suitable automatic feeding device, just far enough so that it will not fall out, and then in the rotation of the drum the presser member will be caused to swivel back on its axis to bring the presser arm 19 into alinement with the shell casing. Any suitable means may be provided to cause this return swiveling movement of the presser member. One 85 means for doing this is to make fast one end 34 of the spring 20 to the drum, and to make fast the other end 35 to the lower end of the arm 18 of the presser member so that when the presser member is swiveled on its axis by means of the cam 25 to turn the presser arm 19 out of alinement with the shell casing, the said spring 20 will be wound up, and when the projection 24 on 90 the presser member rides off of the cam 25 the tension of the spring 20 will cause the presser member to swing back into alinement with the opening in the die. In the meantime, however, the shell which has been 95 reformed should be ejected and another shell should be introduced into the die before the presser 19 swings back into operative position.

The operation of the machine therefore is 100 as follows: The drum 1 is rotating, preferably continuously. At the proper station when the die 11 is empty and the presser member 19 is out of alinement therewith a shell should be introduced partway into the die and held therein until in the rotation of 105 the drum the presser arm 19 comes into alinement with the end of the shell casing. Then the roller 22 will begin to ride up on the incline 36 of the cam 23, at which time the presser arm 19 will begin to press the 110 shell casing into the die and it will hold the shell casing within the die as long as the roller 22 rides along on the high part of the cam 23. The forcing in of the shell casing will smooth out and true up the exterior periphery of the shell casing. It is not 115 so essential to smooth out the interior surface of the shell casing, or even to entirely obliterate inward bendings of the exterior 120 surface of the shell casing, but it is impor- 125 130

tant and essential that there shall be no outward bulges and also that the exterior surface shall be substantially cylindrical and it shall not be jammed into elliptical form in 5 cross-section, it being absolutely essential that the exterior surface shall be such that it will slide easily in the barrel or chamber of the gun, or whatever other shell using weapon may be employed. In the continued 10 rotation of the drum the projections 24 mounted on the presser member engages with the cam 25 and thereby the presser member is turned out of engagement with the shell and out of alinement with the die 15 and the shell is then ejected in the manner already described.

What I claim is:—

1. A machine for reforming mutilated shell casings having a rotary member provided with a plurality of dies, each shaped to give correct form to a mutilated casing, a plurality of presser members equal in number to the dies mounted on the die carrier and adapted to be moved into and out of 25 operative relation to the dies, means for rotating said die carrier, means for forcing each presser member in respective order toward the die to force a casing into the die when the carrier in its rotation reaches a 30 predetermined point, means for retracting the presser member at a predetermined point after the casing has been forced into the die, and means for swinging the presser member out of alinement with the die after 35 it has been withdrawn from the die.

2. A machine for reforming mutilated shell casings having a rotary member provided with a plurality of dies, each shaped to give correct form to a mutilated casing, a plurality of presser members equal in number to the dies mounted on the die carrier and adapted to be moved into and out of operative relation to the dies, means for rotating said die carrier, means for forcing each presser member in respective order toward the die to force a casing into the die when the carrier in its rotation reaches a predetermined point, means for retracting the presser member at a predetermined point 45 after the casing has been forced into the die, means for swinging the presser member out of alinement with the die after it has been withdrawn from the die, and means for engaging the casing and ejecting it from 50 the die after it has been forced in by the presser member when the presser member has withdrawn.

3. A machine for reforming ammunition shell casings comprising a rotary member having mounted therein a plurality of female dies shaped to the contour of the casing in its true form, movable presser members which are mounted on said rotary die carrier, a presser member for each die, and 60 which are movable into and out of alinement

70 ment with the dies respectively in addition to their movement bodily with the carrier, means which during the rotation of the die carrier causes each presser member at a certain period in its travel with the die carrier, to move into alinement with its die at some distance outward therefrom, means for then pressing the presser member inward and thereby forcing a casing into the die, if a casing has been properly positioned 75 therefor, means for causing the retraction of the presser member at a predetermined point in the rotation of the carrier, and means for causing the presser member to also move out of alinement with the die. 80

4. A machine for reforming ammunition shell casings comprising a rotary member having mounted therein a plurality of female dies shaped to the contour of the casing in its true form, movable presser members 85 which are mounted on said rotary die carrier, a presser member for each die, said presser members being movable into and out of alinement with the dies respectively in addition to their movement bodily with the carrier, means which during the rotation of the die carrier causes each presser member at a certain period in its travel with the die carrier, to move into alinement with its die at some distance outward therefrom, means for then causing the presser member to move 90 inward and thereby force a casing into the die, if a casing has been properly positioned therefor, means for causing the retraction of the presser member at a predetermined point in the rotation of the carrier, and for 95 causing the presser member to also move out of alinement with the die, and means for causing the casing to be pushed outward from the die at a predetermined point in the 100 rotation of the carrier after the presser has been withdrawn.

5. A machine for reforming ammunition shell casings comprising a rotary carrier having mounted therein a die shaped to the 110 contour of the casing in its true form, means for rotating the carrier, a movable presser member which is mounted on said carrier and which is movable into and out of alinement with the die in addition to its movement bodily with the carrier in a rotary path, means which during the rotation of the die carrier causes the said presser member to move inward when in its alined position and thereby force the casing into the 115 die, if a casing has been properly positioned therefor at the entrance to the die, means for causing the retraction of the presser member from the die, means for turning the presser member out of alinement with the die after it is retracted, and means for again moving the presser member into alinement with the die. 120

6. A machine for reforming ammunition shell casings comprising a rotary drum hav- 125

ing a plurality of female dies mounted there-in, arranged in a series concentric with the axis of the drum, means for rotating the drum, a plurality of siphon shaped presser members, the long arm of each of which is mounted slidably in a socket in the drum, there being one of said presser members adjacent each die, and means whereby at a certain period in the rotary movement of said drum, said presser member is forced inward causing the short arm of the presser member to engage with a casing and force it into the die, if the casing has been previously positioned in the mouth of the die.

15 7. A machine for reforming ammunition shell casings comprising a rotary drum having a plurality of female dies mounted therein, arranged in a series concentric with the axis of the drum, means for rotating the
20 drum, a plurality of siphon shaped presser members, the long arm of each of which is mounted slidably in a socket in the drum, there being one of said presser members adjacent each die, means whereby at a certain
25 period in the rotary movement of said drum, said presser member is forced inward causing the short arm of the presser member to engage with and force into the die a casing, if the same has been previously positioned in the mouth of the die, the long arm of the presser member being rotatable as
30 well as slidably in its socket bearing, means for swiveling said presser member, and means for controlling the swiveling action
35 whereby the presser arm will be swung out of alignment with the die after it has forced the casing into the die.

8. A machine for reforming ammunition shell casings comprising a rotary drum having a plurality of female dies mounted therein, arranged in a series concentric with the axis of the drum, means for rotating the drum, a plurality of siphon shaped presser members, the long arm of each of which is mounted slidably in a socket in the drum, there being one of said presser members adjacent each die, means whereby at a certain period in the rotary movement of said drum, said presser member is forced inward causing the short arm of the presser member to engage with and force into the die a casing, if the same has been previously positioned in the mouth of the die, the long arm of the presser member being rotatable as well as 55 slidable in its socket bearing, means for swiveling said presser member, means for controlling the swiveling action whereby the presser arm will be swung out of alignment with the die after it has forced the casing 60 into the die, means for causing the outward retraction of said presser member, and means for swiveling the presser member so as to bring the short arm again into alignment with the die at some distance outward 65 from the entrance thereto.

9. A machine for reforming ammunition shell casings comprising a rotary drum having a plurality of female dies mounted therein, arranged in a series concentric with the axis of the drum, means for rotating the drum, a plurality of siphon shaped presser members, the long arm of each of which is mounted slidably in a socket in the drum, there being one of said presser members adjacent each die, the short arm of the presser member being movable in alinement with the die, and means whereby at a certain period in the rotary movement of said drum, said presser member is forced inward causing the short arm of the presser member to engage with and force into the die a casing, if the same has been previously positioned in the mouth of the die, the long arm of the presser member being rotatable as well as slidable in its socket bearing, means for swiveling said presser member, means for controlling the swiveling action whereby the presser arm will be swung out of alinement with the die after it has forced the casing into the die, means for causing the outward retraction of said presser member, and means for swiveling the presser member so as to bring the short arm again into alinement with the die at some distance outward from the entrance thereto, a reciprocable plunger slidable within the die and through the base thereof, and means for reciprocating said plunger so controlled and timed with relation to the movement of the drum and of the presser member that after the shell casing has been forced into the die and the presser member withdrawn therefrom, said plunger will be moved outward to engage the head of the casing and push it outward from the die. 100

10. A machine for reforming ammunition 105
shell casings having a rotary die holder, a
die mounted in said holder shaped to re-
ceive and reform a mutilated shell casing, a
clamping member partially surrounding the
said die, a recess in the die holder in which 110
said clamping member is set, said clamping
member having a flange which engages the
outer end of the die, and means for securing
the clamping member to the die holder.

11. A machine for reforming ammunition shell casings having a rotary die holder, a die mounted in said holder shaped to receive and reform a mutilated shell casing, a siphon shaped presser member, the die carrier being formed in a recess in which the long arm of the presser member is reciprocable, the short arm of the presser member being adapted to be in alignment with the entrance of the die when the long arm of the presser member is in a certain position on its axis, said long arm being rotated on its axis to swing the short arm of the presser member out of alignment with the die, means for forcing the long arm of the presser member outward to cause the short arm to 130

be moved axially outward away from the die carrier, a cam which during a certain point in the rotation of the die carrier moves the presser member inward causing the short arm of the presser member to move inward with relation to the die, a projection on said presser member, a cam with which said projection on the presser member engages at a

certain period in the rotation of the die carrier whereby the presser arm is swung out 10 of alinement with the die, and means which at another stage in the movement swings the presser arm into alinement with the die.

In testimony whereof I affix my signature.

FRANK LEMING.
